DESIGN FOR A HOBBY HORSE

Ben Rosenberg, Los Angeles, Calif., assignor to
Max L. Holzman and Sara W. Holzman, Long Beach, Calif.

Application July 4, 1945, Serial No. 120,510

Term of patent 14 years

(Cl. D34—15)

To all whom it may concern:

Be it known that I, Ben Rosenberg, a citizen of the United States, residing at Los Angeles, in the county of Los Angeles and State of California, have invented a new, original, and ornamental Design for a Hobby Horse, of which the following is a specification, reference being had to the accompanying drawing, forming part thereof.

Fig. 1 is a perspective view of a hobby horse showing my new design.

Fig. 2 is a side elevational view of the same.

I claim:

The ornamental design for a hobby horse, as shown.

BEN ROSENBERG.
